BION C. PLACE, OF DETROIT, MICHIGAN, ASSIGNEE OF ONE-HALF TO GEORGE E.
GAGNIER, OF DETROIT, MICHIGAN

VEHICLE BODY TRIM PANEL

Application filed July 17, 1929. Serial No. 378,965.

This invention relates to a trim panel for vehicle bodies, such as automobile or aircraft bodies.

Heretofore, panels used for this purpose have generally been constructed of a fibrous foundation or body to the external face of which is applied a suitable finishing cloth. The foundation or body has been made of relatively rigid fibre boards designed to provide the necessary stiffness to the panel. Attempts have been made to emboss such fibrous panels, but such efforts have not been successful, because the fibre boards of which the foundation or body of the panel was constructed did not permit the die-shaping of the panel, because such material was liable to rupture or tear or become seriously weakened by the action of the dies in embossing the panels. The attempts that have heretofore been made have been accordingly, generally regarded as unsatisfactory. Such panels also did not permit the edges to be bent back on the body without substantial weakening thereof.

Certain types of panels intended for the finishing of the interior of vehicle bodies, such as automobile body, and constructed as just described, have heretofore been provided with a pocket. Such panels are usually applied to the inside of the doors of vehicle bodies. It has been the practice heretofore, in constructing a trim panel including a pocket, to stamp out the central portion of the panel including the foundation or body as well as the fabric covering in the outline of the pocket. This is done in order that the pocket that is subsequently applied may be disposed in the recess thus provided and lie substantially flush with the outside of the panel. A pocket applied in this way serves to enhance the appearance of the completed panel. In such construction, however, the pocket had to be applied to the perforated panel by sewing the pocket upon a suitable foundation or body of stiff fibrous material having transverse dimensions exceeding the transverse dimensions of the opening cut in the panel itself. The pocket was sewed upon this strip of material and such material, including the pocket, was then stitched to the

panel itself against the rear face thereof with the pocket thereof protruding through the opening that was formed in the body of the panel. The construction thus provided is ornamental in appearance, because the pocket lies flush with the surrounding sides of the panels but the production of the panels is relatively expensive because of the number of operations that are required in order to complete its manufacture, and because of the waste of material resulting from the punching out of the central portion of the body of the panel and the utilization of another piece of fibre board having dimensions greater than that punched out to serve as a foundation for the pocket itself, and to bridge the opening thus formed in the panel.

This invention aims to produce a trim panel for the interior of vehicle bodies, including a foundation or body constructed of such material that it may be embossed by means of dies without rupturing the material or seriously weakening it at the points in which the embossing action takes place, and that will at the same time permit the margins of the panel, after the cloth covering has been applied thereto, to be bent around back upon the foundation or body itself, presenting nicely rounded and strengthened edges that greatly improve the appearance of the panel. Such folding of the edges cannot be successfully brought about in panels that include fibrous body material, as above stated, because said material will not permit the return bending of the edges thereof without substantial weakening or breaking. If the foundation or body of the panel is constructed of steel reinforced fibre board, in accordance with this application, it has been found to be entirely feasible to score or corrugate the edges of the panel at their line of fold to facilitate the turning back of the margins, producing nicely rounded edges, and in the same operation, to emboss the body of the panel to give it an ornamental appearance and in the same operation to depress the central portion of the body of the panel, so that the pocket, when one is used, may be sewed into the depression thus formed with all of the advantages attendant upon the attachment

of a pocket to a trim panel in which the foundation or body is provided with an opening to receive the pocket material after the manner above described, and further additional 5 advantages that lower the cost of production, and improve the panel considered as a whole.

The primary object of this invention accordingly is, to provide a trim panel for vehicle bodies, such as an automobile or aero- 10 plane body for example, in which the foundation or body of the panel is constructed of steel reinforced fibre board, that is shaped by means of dies in a single operation to give an ornamental effect to the body of the panel, 15 to provide an integral foundation for the pocket subsequently attached thereto, and to score the edges of the body of the panel so that they may be readily folded back upon the body to provide a panel having nicely 20 rounded and unbroken edges, when such edges are deemed desirable.

A further object of the invention is to produce a trim panel including a foundation or body and a fabric covering, as well as a separate 25 pocket attached thereto, in which the foundation or body of the panel and the material that has heretofore formed the back of the pocket consist of a unitary integral sheet of material.

30 A still further object of the invention is to provide an improved manner of securing the pocket, that forms an essential part of certain trim panels intended for finishing the interior of vehicle bodies, that will enable 35 the pocket to be readily attached to the body of the panel itself, presenting a flush-job of superior appearance and workmanship, than the trim panels embodying pockets that fit into openings formed in the body of the panel 40 itself, such as are now commonly used in automobile bodies of certain types.

Further objects of the invention will appear as a description thereof proceeds with reference to the accompanying drawings in 45 which;

Fig. 1 is a face view of a panel constructed in accordance with this invention, the pocket being omitted.

Fig. 2 is a face view of the same panel, with 50 the pocket applied thereto.

Fig. 3 is a transverse section of the panel taken on the plane indicated by the line 3—3 of Fig. 1.

Fig. 4 is an enlarged fragmentary sectional 55 view of the body of the panel.

Fig. 5 is an enlarged fragmentary sectional view taken on the plane indicated by the line 5—5 in Fig. 2.

Fig. 6 is a fragmentary sectional view of 60 the edge of the pocket, taken on the plane indicated by the line 6—6 on Fig. 2.

Fig. 7 is a sectional view of the completed panel showing the mode of attachment of the pocket thereto in the depression formed 65 therein, the plane in which this figure being

taken, being indicated by the line 7—7 on Fig. 2.

Like reference characters indicate like parts throughout the several figures.

In the drawings, the numeral 10 indicates 70 the foundation or body of the improved panel of this invention. Said body is constructed of fibrous material provided with a wire reinforcement 11. Preferably, steel wire of a relatively small mesh is employed, 75 and in the manufacture of the foundation or body 10, said wire is arranged between two layers of fibrous material and is subjected to sufficient pressure to compress the layers on opposite sides of the wire fabric to unite 80 through the interstices thereof to form a substantially integral structure. An improved fibre board having the characteristics necessary to the carrying out of the invention about to be described, is disclosed in Patent 85 #1,770,521 granted July 15, 1930.

A panel constructed as just described is capable of being corrugated or embossed to substantial depths by die-shaping. In this respect it is substantially different from 90 the ordinary fibrous material heretofore used as the body or foundation of a trim panel. Ordinary fibrous material cannot be deeply embossed or corrugated without tearing or so weakening the fibre as to render the panel 95 substantially useless.

Applied to one side of the foundation or body 10 is a cloth covering 12, that is cemented thereto by a flexible cement, preferably, of a water-proof character. The material from 100 which the panels are made is formed in continuous webs and the panels are preferably stamped therefrom and embossed in a single operation, by a combined die-shaping and die-cutting operation as hereinafter pointed 105 out.

One form which a trim panel may take, is illustrated in Fig. 1 of the drawings. It comprises, as will be clear from an inspection of this figure, a central raised embossed portion 13, the mid-portion 14 of which is depressed to return said portion substantially to the plane of the side edges 15 or the unembossed portions of the panel. The central portion 13 may assume any ornamental 110 character that may be desired. The depressed portion 14 is made in the form of the desired outline of a pocket, that is subsequently applied in such depression in the manner hereinafter pointed out.

The appearance of the panel is greatly enhanced if the margins thereof are turned back upon the body to provide strengthened, nicely rounded and finished appearing edges. In accordance with this invention, when it is desired to utilize panels having such rounded and bent-back edges, the panel is preferably scored adjacent the edges thereof by pressing a corrugation 16 around the entire periphery thereof at a point spaced from 115 120 125 130

the edges of the panel a distance equal to the desired turned back portion. In order to facilitate the formation of neat appearing corners of the panels, they may be cut out as 5 is shown at 17 leaving tongues 18 at the corners of the panel, that are likewise turned back upon the body. Such turned-back portions may be provided with suitable openings to receive spring fasteners of any form 10 by which the panel may be secured to the foundation structure. Several ways of forming the margins to facilitate their attachment to the supporting structure, are illustrated in my copending application Ser. No. 15 378,964 filed July 17, 1929.

It should be understood however, that when panels are provided that do not have the turned back portions and the rounded edges provided thereby, the corrugations adjacent the margins of the panel, may be simply omitted, and in this case the panel 20 would be stamped out in a form to accurately fit the contour of the surface to which it is subsequently to be applied.

25 As above indicated, the panel may be stamped from a web of material and embossed and corrugated at a single operation of a die, that is formed to provide the necessary cutting edges and shaping surfaces at 30 the points thereof necessary to obtain a panel having the desired outline and ornamentation. During the same operation, suitable openings such as indicated by the numerals 19, 20 and 21 are punched in the panel by 35 properly positioned and formed punches carried by the dies. Such openings may be of any form desired, and may be located in any position as may be necessary to attach the door latches and window operating 40 mechanisms, which usually traverse the trim panel. The openings shown on the drawings are simply illustrative and indicate one arrangement that may be used, but it should be understood that such openings may be located 45 as desired, or if no such openings are necessary, they may be omitted entirely.

It will be observed that the portion of the panel that is designated by the numeral 13 is formed so that it protrudes outwardly 50 from the margins 15 of the panel, and that the depressed portion 14 is arranged so that it extends inwardly to bring the body of the depressed portion substantially in the plane of said margins. The ornamentation of the 55 body of the panel by pressing it outwardly accordingly, provides space in back of the ornamented body into which the portion 14 can be depressed without interfering with the application of a panel to a supporting 60 structure that may be provided with a supporting surface which, in the applied position of the panel may be disposed immediately adjacent thereto. Such depressing of the central portion of the panel avoids the 65 necessity for perforating the panel at this

point in order to provide a recess therein to receive a pocket subsequently applied thereto. As above stated, prior to this invention it was the practice to apply such pockets to 70 separate pieces of fibrous material having dimensions greater than the dimension of the opening formed in the panel, to sew the pockets to such pieces of material, and then secure the material to the back of the panel with the pocket protruding through the opening. 75

This invention avoids entirely the use of a separate piece of fibrous material to serve as a stiffening element for the pocket, and to form at the same time the rear side thereof, because in the invention of this application

80 the rear side of the pocket is formed by the depressed portion 14 of the body of the panel and the recess designed to receive the pocket material is provided simply by depressing a portion of the panel itself. The pocket is 85 applied to said depressed portion as indicated particularly in Fig. 2 of the drawings. As shown in this figure and Figs. 5 and 7, the pocket of the panel consists of a piece of fabric cut into suitable outline to give the 90 pocket an ornamental appearance, the piece of material being indicated by the numeral 22. As indicated, it has a rounded lower edge 23 and rounded side edges 24 and 25, the margins of which are doubled as indicated 95 in Fig. 7. The pocket is then set into the depression 14 and is sewed or otherwise secured to the panel as indicated at 27 through the doubled portion thereof. Before the pocket is applied to the panel however, its upper edge is doubled as indicated at 28 (Fig. 6) and secured to the body of the pocket by stitching, or otherwise, 29, providing a loop to receive a strip of elastic material 30 that extends from side to side of the pocket. As 100 indicated in Fig. 2, the material of the pocket is made of sufficient size so that when it is applied to the depression 14 the material between the sides of the pocket will assume a folded condition so as to permit an enlargement of the pocket by pulling it away from the body of the panel against the action of the elastic material 30. The elastic material is 105 secured to the body of the panel in any suitable manner but preferably, as indicated in Fig. 5 of the drawings. As shown in this figure, the elastic material 30 is riveted at each end thereof by means of a rivet 31 to the panel. In order to apply the rivet the cloth covering of elastic material is bent back 110 as indicated at 32 in said figure, to permit the application of the rivet to the panel. After such rivet has been applied the raised portion 32 of the overlapping fabric of the pocket is return-bent as indicated at 33, and 115 the doubled portion of the fabric thus provided is stitched, as indicated at 34, to the panel, such stitching serving to complete the application of the pocket to the panel. Said pocket, it will be understood, lies substan-

120 125 130

tially flush with the outer portion of the central embossed portions 13 of the panel. It should be understood however, that the pocket may extend outwardly slightly beyond the 5 plane of said portion of the panel, or it may be depressed inwardly beyond said plane, as may be desired.

In the use of the invention just described, suitable foundation material, consisting of a 10 fibrous body reinforced with a steel wire of relatively small mesh and provided with a fabric covering 12 of any suitable character, is preferably provided in the form of a continuous web. Said web is then cut and shaped between 15 cooperating dies provided with cutting elements that serve to stamp out a panel in the desired form and to punch openings of the desired character in the body thereof. The cooperating dies are provided with shaping 20 projections and recesses arranged to simultaneously form the corrugation 16, when such a corrugation is desired and the raised or ornamental portion 13 and the depression 14 of the body of the panel. The web of 25 material is advanced intermittently beneath dies of the character just stated, and the panels are stamped and formed in a single operation by said dies. A panel is thus provided that may readily be strengthened, by 30 bending back the edges, and ornamented, and may readily receive the cloth pocket ordinarily associated with some types of door panels. Such pocket is then applied to the depression 14 formed in the panel in the manner above 35 described.

The application of the pocket to the panel is no more difficult than the application of the pocket to the separate piece of fibrous material heretofore used and applied to the 40 rear of a perforation or opening in said panel. At the same time, the panel consisting of an integral structure possesses greater strength and rigidity than in constructions heretofore proposed in which the body of the panel was 45 perforated, and in which a separate piece of material was applied to the rear thereof. At the same time the number of operations necessary to complete a trim panel is reduced, lowering the cost of production of panels of 50 this character. As above indicated, the panel may or may not be provided with a corrugation surrounding the edges thereof, and permitting the return bending of said edges to provide a rounded and reinforced edge. 55 Such turned back portions may be used as the fastener securing portions of the panel. If such turned back edges are not desired, the panel is punched out in the form and outline necessary to fit the particular outline of the 60 wall or supporting surface to which it is to be applied.

The invention may be embodied in other specific forms without departing from the spirit or essential characteristics thereof.

65 The present embodiment is therefore to be

considered in all respect as illustrative and not restrictive, the scope of the invention being indicated by the appended claims rather than by the foregoing description, and all changes which come within the meaning and range of equivalency of the claims are therefore intended to be embraced therein.

What I claim as my invention is:

1. A trim panel comprising a body, and a fabric covering applied to one side of said body, said body and fabric having a depression pressed therein in position to receive a pocket with its outer surface approximately flush with the portions of the panel surrounding said depression, the sides of said depression being in the outline of said pocket.

2. A trim panel comprising a body and a fabric covering applied to one side of said body, said body and fabric having the central portion thereof embossed toward said side, and said embossed portion being formed with a depression arranged in position to receive a pocket with its outer surface approximately flush with the portions of the panel surrounding said depression, the sides of said depression being in the outline of said pocket.
